(57) **CLAIM**

The ornamental design for an all-in-one computer, as shown and described.

DESCRIPTION

1. All-in-one computer

1.1 : Perspective

1.2 : Rear perspective view

1.3 : Front

1.4 : Back

1.5 : Left

1.6 : Right

1.7 : Top

1.8 : Bottom

The present design is for an all-in-one computer comprising of a computer built into a monitor with a Radio Frequency Identification (RFID) module; the RFID module is built in the lower front of the monitor, and it is possible to improve security and convenience by logging in and by tagging a card or the like; the broken lines indicate portions of the article that form no part of the claimed design.
